(57) **CLAIM**

I claim, the ornamental design for a cookware handle, as shown and described.

DESCRIPTION

FIG. 1 is a top perspective view of a cookware handle, showing my new design;

FIG. 2 is a bottom perspective view thereof;

FIG. 3 is a front view thereof;

FIG. 4 is a rear view thereof;

FIG. 5 is a top plan thereof;

FIG. 6 is a left side view thereof, the right side view being a mirror image thereof; and,

FIG. 7 is a bottom plan thereof.
